UNITED STATES PATENT OFFICE.

GUSTAV FRENKEL, OF DELMENHORST, GERMANY.

MACHINE FOR MANUFACTURING LINOLEUM.

SPECIFICATION forming part of Letters Patent No. 793,031, dated June 20, 1905.

Application filed June 26, 1903. Renewed August 29, 1904. Serial No. 222,605.

To all whom it may concern:

Be it known that I, GUSTAV FRENKEL, a subject of the German Emperor, residing at Deldenhorst, Germany, have invented certain new and useful Improvements in Machines for Manufacturing Linoleum, of which the following is a specification.

The said invention relates to a machine or apparatus for manufacturing linoleum in which the pattern extends through the material; and the object of the invention is to provide a simple, economical, durable, and effective machine capable of producing linoleum in as rapid a manner as possible and at a low cost.

To this end the invention consists, broadly, in a machine or apparatus for applying granular material to a supporting or backing strip having means for moving the backing strip or sheet intermittently and a stencil-plate with means for moving it with the backing-sheet and raising it and returning it to initial position while the sheet is at rest.

The invention further includes the various features of construction and arrangement of parts, as hereinafter described, and particularly pointed out in the appended claims, which fully and clearly define the invention and distinguish it from the state of the art.

The invention is illustrated in the accompanying drawings, in which—

Figure 1 is a longitudinal vertical section through the center of the machine. Fig. 2 is a plan view, partly in section. Figs. 3 and 4 are detail views. Fig. 5 is an enlarged sectional view with parts omitted. Fig. 6 is a sectional view of the wheels ω .

Referring by reference characters to the figures, in which the same parts are designated by the same letters throughout the several views, the driving-shaft to which the power is transmitted for operating the machine is shown at a . This carries a beveled gear b , which engages with a beveled gear b' on a shaft c , longitudinally disposed centrally of the machine, which at its opposite end carries a beveled gear b^2 , meshing with beveled gears b^3 and b^4 , loosely journaled on a shaft e , which through connections hereinafter described operates to reciprocate the stencil-

plates t^4 . The beveled gears b^3 and b^4 are both loose upon the shaft e and are designed to be alternately clutched to the shaft by a clutch member f , having frusto-conical friction-disks d and d' , which engage with corresponding recesses in the gears b^3 and b^4 , and which may have their friction-surfaces covered with leather or any other approved material for assisting in procuring the frictional engagement.

The clutch member f is operated automatically to engage first one gear and then the other, and thereby automatically reciprocate the stencil-plates, by means of a cam g , mounted on the shaft c , which engages a roller i , carried by one arm of a bell-crank lever h , secured on a shaft c' , the opposite arm being provided with a weight l , by which the roller is held constantly in contact with the surface of the cam g . This shaft c' also carries an arm h' , which is provided with rollers h^2 , which engage or rest in the groove of the clutch, so that as the cam g rotates the arm h' will be rocked and the clutch f accordingly thrown into frictional engagement first with one gear and then with the other.

The shaft e carries at its opposite ends drums k , upon which are wound and secured the end portions of bands e' and e^2 . The bands e' lead rearwardly around an idle pulley n and connect with a cross-bar l , which has its end portions resting in vertical slots t^5 of brackets t^3 , which are secured to bars t' , which support the stencil-plates. The bands e^2 lead forwardly from the drums and passing around a pulley or wheel ω are secured in their turn to the front sides of the bars l . These bands e^2 are preferably provided with projections o' , which engage in corresponding recesses o^2 in the peripheries of the wheels, whereby the bands and wheels are caused to move in unison. It will thus be seen that as the shaft e is operated in the manner described the bands e' and e^2 will be alternately wound and unwound upon the drums k , with the result that the cross-bar l will be caused to travel back and forth in the guiding-recess m of the frame, and through its connection with the rails t' by the brackets above referred to the rails will be reciprocated longitudinally of the machine and with them the stencil-plates t^4 .

In order to move the backing-sheet forward while the stencil-plates are moving forward and to hold it stationary while the stencil-plates are being carried back to an initial position, I provide on the shaft c^2 additional pulleys or wheels, over which pass bands p , these bands passing at the rear of the machine over idle pulleys C , which are preferably mounted in adjustable bearings, so that any slack in the bands may be taken up. These bands likewise have projections which engage recesses in the driving-pulley, whereby slipping is prevented in the same manner as by the projections and recesses o^1 and o^2 , already referred to. The wheels upon which the bands p travel and by which they are driven are provided with bosses or projections o^5 within the peripheral rim of the wheels o , to which are pivotally mounted clutch-arms o^3 , so arranged that on the forward movement of the parts in the direction of the arrow z the clutch members o^3 will be engaged by the wheel o , and consequently the wheels around which the bands p pass will be rotated. On the backward movement of the cross-bar l and its bands the clutch-arms o^3 will be disengaged, whereby bands p will be held stationary. It will of course be understood that the backing-sheet upon which the granular material is laid or deposited by the stencil-plates is carried by these bands p .

It will be obvious that it will be necessary to raise the stencil-plates above the sheet of material while they are being moved backwardly. To provide for this and to enable their being more easily moved, I mount them upon antifriction-bars t^2 , which are carried by arms a' , mounted on rock-shafts which are rocked by an arm a^2 , operated in turn by suitable connections (indicated at a^3) from the shaft a .

At the beginning of the operation the stencil-plates rest upon the backing-sheet and move forward in unison therewith in the direction of the arrow z , Fig. 1. During this time the stencil-plates receive the granular material from the troughs r , which are held against longitudinal movement, and consequently deposit the material in an even layer upon the stencil-plates as the latter move forward. In order to cause a more even distribution of the material, each trough is provided with a grid s , having cross-pieces s' , and which is reciprocated transversely of the machine by an eccentric connection with the shaft u . The troughs or hoppers r are held against movement by U-shaped brackets u' , which engage bosses on the shaft u . The grid s is preferably guided by antifriction-rollers r^2 and r^3 , carried by the trough r . It will be understood that in Fig. 1 the stencil-plates are supposed to be at the limit of their forward movement and about to be reversed.

After the backing-sheet, with the granular material deposited thereon, leaves the con-

veyer-bands p it is passed through a suitable press a in order to receive a preliminary pressing and is then wound upon a cylinder or roller y , which of course must be operated intermittently in unison with the remainder of the machine.

Having thus described my invention, what I claim is—

1. A machine for applying a granular covering material to a backing-sheet, comprising means for moving the backing-sheet, intermittently, and a stencil-plate with means for moving it with the backing-sheet and raising it and returning it to initial position while the sheet is at rest.

2. A machine for applying a patterned covering material to a backing-sheet comprising means for supporting and moving the backing-sheet intermittently, a plurality of stencil-plates, means for raising and lowering them, and means for reciprocating the stencil-plates in unison with the intermittent movements of the sheet, substantially as described.

3. A machine for covering backing-sheets with granulated covering material comprising stencil-plates, means for moving said stencil-plates together with the backing-sheets, for stopping the sheets when covered, and for raising and returning the said stencil-plates to their initial position and for conveying the sheets to a preliminary press.

4. A machine for covering backing-sheets with granulated covering material comprising stencil-plates, means for moving said stencil-plates together with the backing-sheets, for stopping the sheets when covered, and for raising and returning the said stencil-plates to their initial position and for conveying the sheets to a preliminary press and thence to a calendar.

5. A machine for applying patterned covering material to a backing-sheet comprising a suitable frame or table, bands for supporting the sheet with means for reciprocating them, and vertically movable and reciprocating stencil-plates with means for operating them substantially as described.

6. A machine for applying covering material to a backing-sheet comprising a suitable frame or table, intermittently-moving bands for supporting the backing-sheet with means for operating them, vertically and longitudinally movable rails on opposite sides of the table with means for operating them and stencil-plates mounted on said rails, substantially as described.

7. A machine for applying covering material to a backing-sheet comprising a suitable frame or table, stencil-plates with means for moving them lengthwise of the table and for raising and lowering them, intermittently-moving bands for supporting the sheet, and an intermittently-operated winding-drum upon which the coated sheet is wound.

8. A machine for applying covering mate-

rial to a backing-sheet comprising a suitable frame or table, stencil-plates with means for moving them lengthwise of the table and for raising and lowering them, intermittently moving bands for supporting the sheet, and an intermittently-operated winding-drum upon which the coated sheet is wound, and a pressing device located between said drum and coating device.

- 10 9. In a machine for coating suitable backing-sheets, a suitable frame or table, vertically-movable rails on opposite sides of said table with means for raising and lowering them, an oscillating shaft, bands connected with said shaft and also with said rails whereby the oscillation of said shaft reciprocates the rails, and intermittently-operated means for guiding the backing-sheets, substantially as described.
- 15 10. A machine for applying a granular covering material to a backing-sheet, comprising means for moving the backing-sheet intermittently, a stencil-plate with means for moving it with the backing-sheets and raising it and returning it to initial position while the sheet is at rest, and a stationary hopper co-operating with said stencil-plate, substantially as described.

- 20 11. A machine for applying a patterned covering material to a backing-sheet comprising means for supporting and moving the backing-sheet intermittently, a stencil-plate, means for raising and lowering it and for reciprocating the stencil-plate in unison with the intermittent movements of the sheets, a stationary hopper co-operating with said stencil-plate, and agitating means in said hoppers, substantially as described.
- 25 12. A machine for covering backing-sheets

with granular covering material comprising 40 stencil-plates, means for moving said stencil-plates together with the backing-sheets, for stopping the sheets when covered, and for raising and returning the said stencil-plates to their initial position, a stationary hopper 45 co-operating with each stencil-plate, a grid in each hopper, and means for reciprocating the grids in the hoppers, substantially as described.

13. A machine for applying covering mate- 50 rial to a backing-sheet comprising a suitable frame or table, intermittently-moving bands for supporting the backing-sheet with means for operating them, longitudinal rails on opposite sides of the table, and stencil-plates 55 mounted on said rails, antifriction devices slidingly supporting said rails, means for raising and lowering said antifriction devices, and means for reciprocating the rails, substantially as described.

- 60 14. In a machine for coating suitable backing-sheets, a suitable frame or table, vertically-movable rails on opposite sides of said table with means for raising and lowering them, an oscillating shaft, bands connected 65 with said shaft and also with said rails whereby the oscillation of said shaft reciprocates the rails, intermittently-operating means for guiding the backing-sheets, stencil-plates carried by said rails, and stationary hoppers co- 70 operating with said stencil-plates, substantially as described.

In testimony whereof I affix my signature in presence of two witnesses.
